UNITED STATES PATENT OFFICE.

JOHN S. CANTELO, OF TAUNTON, MASSACHUSETTS.

ADJUSTABLE DRAWING-KNIFE.

SPECIFICATION forming part of Letters Patent No. 286,385, dated October 9, 1883.

Application filed March 11, 1882. Renewed October 27, 1882. Again renewed May 19, 1883. (No model.)

To all whom it may concern:

Be it known that I, JOHN S. CANTELO, of Taunton, in the county of Bristol and State of Massachusetts, have invented certain new and 5 useful Improvements in Drawing-Knives; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a view showing my improved drawing-knife with the handles folded down 15 upon the cutting-edge, so as to protect the latter. Fig. 2 is a view, partly in section, showing the handles in their proper position for using the knife, the dotted lines indicating different adjustments of the handles; and 20 Fig. 3 is a cross-section through line x x , Fig. 1.

Similar letters of reference indicate corresponding parts in all the figures.

My invention contemplates certain improvements in so-called "drawing-knives" or shaving-knives, which are used by coopers, wagon-makers, and carpenters (usually in connection with a "shaving-horse") for holding staves, spokes, shingles, ax-handles, or other 30 articles to be shaved.

My said improvements consist in the construction and arrangement of folding and adjustable handles, which, when the knife is not in use, may be folded down upon the cutting-edge, so as to protect the latter, and may also be adjusted at different angles to the knife-blade, substantially as and for the purpose hereinafter more fully set forth.

In the accompanying drawings, A represents the knife-blade, which may be of any suitable length and width, and has a sharp (and preferably slightly rounded) cutting-edge, a . The body of the knife-blade has at each end a disk, B, having a series of circumferential notches, b , and a central hole, c , through which a screw or pin, C, is inserted, on which the handles D are pivoted. The latter are slotted longitudinally, as shown at d , and are bent to form disk-shaped ears D', between which the notched end disks, B, of the knife are inserted.

E E are spring-catches, of any suitable construction, which are inserted into the upper recessed parts of the handles D. Each of these catches or latches is provided with a 55 projecting thumb-piece, e , and a lug, f , adapted to fit into any one of the notches b of its appropriate disk B.

From the foregoing description, taken in connection with the drawings, the advantages 60 of my improvement will readily be understood. By pressing upon the thumb-pieces e the catches E are released, so that the pivoted handles may be folded down upon and over the edge a , as shown in Figs. 1 and 3, so as to 65 cover and protect the latter when the knife is not in use. Again, when the knife is to be used the handles may be adjusted in different positions or at different angles to the knife-blade, as shown in Fig. 2, in which the full-line drawings show the position of the handles for ordinary use in shaving hoops or shingles, when extended, as shown in the dotted lines indicated by D'. This position of the handles will protect the hands of the operator and 70 prevent them from coming in contact with the work-bench or shaving-horse, and the position indicated by the dotted lines marked D' 75 represents the adjustment of the handles when it is desired to push the knife instead of drawing or pulling it, or when it is desired to grind the knife-edge.

I am aware that a drawing-knife has been provided with handles which are adjustably held to the shave or knife by a set-screw; and 85 also that a knife has been provided with hinged handles which are held open or closed by a spring; and also that handles have been made so as to receive the edge of the knife for protecting it. In my device the adjustable handles are held at different predetermined positions by a spring-actuated detent or catch on the handle, which engages a notch on the shave. This catch is therefore automatic in 90 its engaging action, and cannot by any possibility become accidentally disengaged by being slipped out of place.

What I claim is—

1. In a drawing-knife, the blade A, having the ends B, provided with notches b , and the handles D, pivoted to such blade at the end, in combination with the spring-actuated catches

E, secured to the handles, and adapted to engage the notches b, as set forth.

2. In a drawing-knife, the blade A a, having the ends B, provided with notches b, and the handles D, provided with the slots d, in combination with catches E and their springs e, such catches and springs being located as described, and the catches adapted to the notches b, all combined and arranged as set forth.

In testimony that I claim the foregoing as my own I have hereunto affixed my signature in presence of two witnesses.

JOHN SOLOMON CANTELO.
